UNITED STATES PATENT OFFICE.

ALEXANDER THOMSON MACFARLANE, OF ROCHESTER, ENGLAND.

ROTARY KILN.

SPECIFICATION forming part of Letters Patent No. 684,996, dated October 22, 1901.

Application filed January 2, 1901. Serial No. 41,820. (No model.)

To all whom it may concern:

Be it known that I, ALEXANDER THOMSON MACFARLANE, a subject of the Queen of Great Britain, residing at Rochester, in the county 5 of Kent, England, have invented a certain new and useful Improvement in Rotary Kilns, of which the following is a full, clear, and exact description, such as will enable others skilled in the art to which it appertains to 10 make and use the same, reference being had to the accompanying drawings, forming part of this specification.

This invention relates to a new and useful improvement in rotary kilns used for the manufacture of cement and the like, and has for 15 its object to dry the powdered coal, slurry, or slip, &c., so that the heat employed in burning the cement or other material in a kiln may also be used as a drying medium, thus 20 utilizing the heat radiated from the kiln and preventing the same from being wasted.

Generally speaking, my invention consists in enveloping a rotary kiln with a casing throughout any desired portion or, for that 25 matter, the whole of its length, into which casing the material to be dried is introduced, means being provided in the casing and attached thereto or to the periphery of the kiln, whereby the material to be dried is not only 30 agitated, so that the little particles thereof are subjected to the drying heat, but said particles of material are propelled from the feed to the discharge end of the drying-chamber.

In the drawings I have shown several forms 35 of my invention applied to a well-known type of rotary kiln.

Figure 1 represents a rotary kiln in elevation with my improved drying attachment arranged in position thereon, said attachment 40 being shown partly in section. Fig. 2 is a vertical cross-sectional view on line 22, Fig. 1. Fig. 3 is a side elevational view of a kiln with my improved drying apparatus in a slightly-modified form in position thereon. Fig. 4 is 45 a sectional view on line 44, Fig. 3.

In the drawings, A indicates a rotary kiln proper, which is preferably arranged slightly inclined, as usual, the forward end of said kiln being received in a hood B, mounted 50 upon a wheeled truck, as is usual, through

which hood finely-pulverized coal is designed to be introduced, as is well understood.

C indicates the stack, into which the rear and elevated end of the rotary kiln is received, said stack carrying off the products of combustion 55 from the kiln. The cement or other material to be burned is introduced into the rear or elevated end of the kiln, and upon ignition of the combustible material introduced at the front end the kiln by being rotated will gradually feed the material therein in a forward direction, the rotation of the kiln presenting different particles of the material to be burned to the action of the heat contained therein.

The kiln proper usually consists of a metallic casing lined inside with fire-brick, annular tracks a being arranged at suitable points on the periphery of the kiln, which tracks coöperate with supporting - rollers, whereby the kiln is supported between its 60 ends. I have not deemed it necessary to show this supporting or driving mechanism in the drawings, as it forms no part of my invention; but I will state that the usual practice, depending upon the length of the kiln, 65 is to arrange supporting-rollers at intervals of about fifteen or twenty feet apart where the kiln is of any considerable length (the kilns being usually from forty to sixty feet long) and that the driving mechanism may 70 be either located at the front end of the kiln or at any other point desired.

Referring now particularly to my improvement, D indicates a casing, preferably of sheet metal, said casing surrounding the body 85 of the kiln proper and extending over any desired portion of its length. As shown in Fig. 1, this casing is located some distance from the body of the kiln, so as to provide the chamber or space into which the material to 90 be dried is introduced. The ends of this casing are preferably closed by suitable walls or flanges, which extend inwardly and embrace the body of the kiln, while openings d are arranged in the top of the casing D for the escape of moisture evaporated from the material being dried.

Suitable supports d' are provided for the casing D to hold it in a stationary position, and an inlet-spout or feed-opening d² is ar- 100

ranged at the side of the casing in Fig. 1 or at the top of the casing, as shown in Fig. 3.

The outlet or discharge opening in the casing is indicated at d^3 , said discharge-opening 5 leading from the bottom of the lower end of the casing and discharging into a suitable receptacle arranged therebeneath, said receptacle being shown in the form of a vessel E, pivotally mounted in a truck-frame.

10 F indicates a spiral blade secured to the body of the kiln within the casing D, said blade extending sufficiently near said casing D to agitate and move the material introduced therein to be dried from the inlet-opening 15 to the discharge-opening. It is obvious that the heat radiated from the kiln will thus be utilized in drying the material in the drying-chamber, above described, the kiln proper carrying the agitating and propelling blades, 20 whereby all particles of material in the drying-chamber are subjected to the drying influence of the radiated heat from the kiln.

In Fig. 3 I have shown a conveyer G for conducting the material to be dried to the inlet-opening d^2 , and instead of having the discharge-opening from the drying-chamber in the bottom portion of the lower end thereof I arrange a series of buckets or elevators at the lower end of the chamber, said buckets 30 being secured to and rotating with the kiln proper, whereby the dried material is elevated or lifted by the buckets and discharged into the spout H.

In Fig. 5 I have shown a construction in 35 which the kiln is provided with flights I to agitate and propel the material to be dried and also a series of buckets I', which lift the material in its passage through the drying-chamber and carry it over the body of the 40 kiln, the material upon reaching the highest point in the drying-chamber being discharged from the buckets and falling over the body of the kiln to the bottom of the drying-chamber, where it is either propelled onward by 45 the flights or again lifted and carried over the kiln, as before described. In this construction I may have either the outlet or discharge opening at the bottom, or the buckets may lift and discharge the dried material at the 50 side, as before described.

I am aware that minor changes in the arrangement, construction, and combination of the several parts of my device can be made and substituted for those herein shown and 55 described without in the least departing from the nature and principle of my invention.

In the event that the drier becomes choked at any time the relief-doors D' in the lower portion of the casing D may be dropped to discharge the load. A screw conveyer D'' 60 may also be used in the bottom of the casing D below the paths of the spirals or angled flights, the purpose of said screw conveyer being to force the material toward the discharge end of the machine, as shown in Fig. 65 7, or this screw conveyer can be used in the bottom of the casing and the spiral or other agitating medium entirely omitted.

Having thus described my invention, what I claim, and desire to secure by Letters Patent, is—

1. In an apparatus of the character described, the combination with a rotary cement-kiln, of a casing enveloping a portion of said kiln, and a device secured to and movable 75 with the rotary kiln, for receiving, agitating, and propelling material to be dried, and which is introduced between the kiln and the enveloping casing, substantially as described.

2. In an apparatus of the character described, the combination with a rotary cement-kiln, of a casing surrounding a portion of the length of said kiln, said casing being provided with heads or inturned flanges at its ends which embrace the kiln and form a drying-chamber, inlet and outlet openings leading to and from said drying-chamber, a device 80 mounted upon the rotary kiln between said heads and within the drying-chamber for agitating and propelling the material to be dried, 85 which material is introduced between the kiln and the casing forming the drying-chamber, substantially as described.

3. In an apparatus of the character described, the combination with a rotary cement-kiln, of a casing surrounding a portion of the length of said kiln and forming a drying-chamber, a spiral blade mounted upon the kiln and rotating therewith in said drying-chamber for agitating and propelling the material to be dried which is introduced in the chamber between the kiln and casing, and buckets secured to the kiln within the casing for elevating the material in the drying-chamber, substantially as described. 95 100 105

In testimony whereof I hereunto affix my signature, in the presence of two witnesses, this 6th day of December, 1900.

ALEXANDER THOMSON MACFARLANE.
